UNITED STATES PATENT OFFICE.

HAROLD S. OSBORNE, OF NEW YORK, N. Y., ASSIGNOR TO AMERICAN TELEPHONE AND TELEGRAPH COMPANY, A CORPORATION OF NEW YORK.

MEANS FOR AND METHOD OF AVOIDING INTERFERENCE.

Application filed July 31, 1918. Serial No. 247,608.

To all whom it may concern:

Be it known that I, HAROLD S. OSBORNE, residing at New York, in the county of New York and State of New York, have invented 5 certain Improvements in Means for and Methods of Avoiding Interference, of which the following is a specification.

This invention relates to signaling systems and particularly to the avoidance of 10 disturbances from outside sources in the conductors of such systems. It finds an especially useful application in the terminal circuits of ocean cables and is here illustrated and described as applied to such a circuit, 15 but it is to be understood that its usefulness is not limited thereto.

As is well known, the signal impulses received over ocean cables are extremely weak and difficult to record as compared with ordinary land line signals and it is customary 20 to reduce the disturbances in the cable circuits by grounding the return circuit at a point at sea often several miles distant instead of at the cable office. This avoids disturbances due to local ground potentials. 25 It does not, however, entirely eliminate disturbing influences because the conductors running from the cable office to the cable and to the sea ground, respectively, may be 30 subject to disturbing potentials induced by neighboring power circuits or the like. It is the object of the present invention to provide means for overcoming these difficulties.

The invention will be more fully understood by a reference to the accompanying drawings in which Figure 1 illustrates diagrammatically one embodiment thereof and Fig. 2 represents a circuit illustrating the 35 conditions to be met.

Fig. 1 shows diagrammatically the ordinary terminal connections for duplex operation of a cable circuit, wherein the cable 1 is connected to the apparatus 2 in the cable office by a conductor 3-4. The recording apparatus 5 is connected between the conductor 3-4 and the artificial line 6, in parallel with the ratio arms 7 and 8 which provide the connecting point for one side of the 45 sending apparatus 9, the other side being grounded, all as is customary in duplex cable operation. Instead of grounding the artificial line 6 and the sending apparatus 9 locally, it is common as above indicated to 50 connect them metallically with a sea ground

to avoid local disturbing potentials. Such a ground connection is indicated on the drawings at 10, with a conductor 11-12 extending between the cable office and the sea ground.

The conductors 3-4 and 11-12 may be subject to disturbing potentials, and due to the unbalanced condition of the circuit with respect to such potentials they will be evidenced in the receiving apparatus 5 to the 65 confusion of transmitted signals. For instance, in the system illustrated in Fig. 1, it may be supposed that a disturbing potential is caused in that section of the conductors 3-4 and 11-12 lying between the dotted lines *a-b* and *c-d*. This potential will ordinarily be of the same sign and magnitude in both of the conductors, as indicated by the arrows *x* and *y*.

The effect of such induced potentials in a 70 circuit of this kind may be readily appreciated by a reference to Fig. 2, in which two conductors 3-4 and 11-12 are supposed to have induced therein similar potentials represented by the arrows *x* and *y*, in that 75 section located between the dotted lines *a-b* and *c-d* as in Fig. 1. If it were not for the fact that each of the conductors has capacity to ground throughout its length and more or less leakage, the induced potentials 80 *x* and *y* if equal would not affect the receiving apparatus 5 since they would neutralize each other therein. For the purpose of illustrating the effect of the leakage and capacity to ground, we may imagine each of 85 the circuits 3-4 and 11-12 to be connected, at the points 3 and 11 respectively, to the common ground 13 through like impedances 14 and 15, as indicated in Fig. 2. The opposite end of the conductor 11-12 is 90 grounded at 10, (the sea ground) while the opposite end of the conductor 3-4 reaches ground 17 only after passing through the entire cable 18 which is of high impedance 95 as compared with the ground 10. Considering, then, the admittance to ground of conductors 3-4 and 11-12 the potentials *x* and *y* are applied to parallel circuits which may be traced, respectively as follows: 4, 3, 14, 13, 17, 18, 4 and 12, 11, 15, 13, 10, 12. 100 The potential *y* is consumed entirely by the impedance of the circuit 11-12 and the impedance 15, the point 12 and ground 10 being regarded as electrically the same for the purposes of this illustration. The potential 110

α is consumed in the impedance of the circuit 4-3 and impedance 14, which are equal to the corresponding impedances of the other circuit, plus the impedance of the 5 cable 18. It is, therefore, obvious that the voltage drop across the impedance 15 will be greater than the voltage drop across the impedance 14; and since the two impedances are connected to the common ground 13, 10 which may be regarded as at zero potential it will be obvious that the point 11 will have a higher potential than the point 3 and that a circuit connected between 11 and 3, such as the receiving circuit 5 in Fig. 1, will receive 15 a current due to this difference of potential.

To correct this condition it is necessary to so vary the impedance between one side of the line and ground that the two terminals 20 are brought to the same potential for all frequencies employed. For this purpose it is necessary that the impedance 3-17 (referring to Fig. 2) be to the impedance 11-10 as impedance 14 is to impedance 15. 25 In a case then such as illustrated in Fig. 2 where 3-17 exceeds 11-10 the impedance at 15 must be made less than the impedance at 14. A convenient method of accomplishing this result in the ordinary cable circuit 30 is to connect an impedance between the point 11 and ground as indicated in Fig. 1. The character of this connection will depend upon the character of the circuit with which it is used. Where the impedance to be balanced 35 consists of resistance and capacity as it frequently will in ocean cables this shunt will consist of like elements as illustrated in Fig. 1, where use is made of a resistance 20 in series with an artificial line 21 the latter comprising resistance and shunt capacity. It will be clear from an inspection 40 of the drawing that such a shunt connected between the point 11 and ground will reduce the impedance between these points and will 45 therefore decrease the potential drop between them, and if properly proportioned will reduce the potential of the point 11 to correspond with that of the point 3 with the result that no current will flow in a circuit 50 connected between them due to the induced potentials α and γ .

It should be understood that the application 55 of the invention is not limited to the case where the potentials α and γ are equal but in any case where they are known the proportion above mentioned between the impedances can be varied to satisfy conditions by adding or subtracting impedance at the proper points as will be obvious.

60 It will be understood, of course, that in the actual circuit the impedance indicated at 14 and 15 in Fig. 2 are distributed along the entire length of the conductors 3-4 and 11-12, but the principle by which the shunt 65 affects the correction remains in general the

same. Theoretically the shunt should be connected at the midpoint of the impedance represented by the conductors 3-4 and 11-12 but since the point at which the disturbances may arise will vary from time to 70 time, no definite point for the connection of the shunt 19 can be assigned and it has been found that the connection of the shunt close to the point 11 will substantially equalize the potentials at 3 and 11 for all induced 75 potentials likely to be met, and throughout a wide range of frequencies. In general the resistance 20 of the shunt 19 should have a magnitude.

$$R = \frac{W(W+r)}{A^2 K} \quad 80$$

where "W" represents the resistance of the sea ground connection, (12, 10 in Fig. 1) "r" is one half the resistance of one of the 85 conductors 3-4 or 11-12, A is the ratio of the resistance of the cable to the capacity of the cable and K is the capacity to ground of one conductor: and the ratio of the resistance of the artificial line 21 to its capacity is 90

$$\frac{(W+r)^2}{K^2 A}$$

Experiments show that in the average ocean 95 cable system, a long artificial line at 21 is unnecessary, a total product of capacity and resistance (K. R) of 0.013 giving practically as good results as larger values. A shorter cable than this, however, gives less 100 perfect neutralization.

The operation of the system will be obvious from the foregoing description. If the points 3 and 11 are brought to the same potential, no current will flow through the 105 apparatus of the cable office connected to these points since whatever is included in the circuit from thereon will have equal and opposite potentials applied thereto. If there is capacity to ground or substantial leakage in 110 the artificial line 6, or other elements of the sending and receiving apparatus, there would be some unbalance in receiving instrument 5, but ordinarily any such leakage or capacity to ground is so small that it may be disregarded. Actual tests with a shunt connection 115 to the circuit, as herein described, show that the disturbances in the receiving instrument 5 are reduced by about ninety per cent. 120

It is to be understood that the invention is not limited to the particular circuits herein shown and described and it will be obvious to those skilled in the art that modifications in details may be made without departing from the spirit of the invention.

What is claimed is:

1. In a signal transmitting system, a metallic transmission line, a duplex set for sending and receiving signals thereover in- 130

cluding an artificial line between which and the main line the receiving instrument of the set is connected, a conductor connecting the duplex set with the ocean cable, a second conductor connecting the transmitting device of the duplex set and the artificial line with ground, and means connected to said last named conductor for equalizing voltages at the terminals of said duplex set, due 10 to potentials induced in said conductors by disturbing outside sources.

2. In a signal transmitting system, a metallic transmission line, a duplex set for sending and receiving signals thereover including an artificial line between which and

the main line the receiving instrument of the set is connected, a conductor connecting the duplex set with the ocean cable, a second conductor connecting the transmitting device of the duplex set and the artificial line 20 with ground, a shunt between said second named conductor and ground and comprising a resistance and an artificial line, for equalizing voltages at the terminals of said duplex set due to potentials induced in said 25 conductors by disturbing outside sources.

In testimony whereof I have signed my name to this specification this thirtieth day of July, 1918.

HAROLD S. OSBORNE.
